Primary Examiner — Mojtaba Tehrani

(57) **CLAIM**

The ornamental design for a wallet, as shown and described.

DESCRIPTION

1. Wallet
- 1.1 : Perspective
- 1.2 : Front
- 1.3 : Back
- 1.4 : Top
- 1.5 : Bottom
- 1.6 : Right
- 1.7 : Left
- 1.8 : Front
- 1.9 : Back
- 1.10 : Top
- 1.11 : Bottom
- 1.12 : Left
- 1.13 : Right

The broken lines do not form part of the claimed design; reproduction numbers 1.8 to 1.13 show the folded state of the product.

1 Claim, 13 Drawing Sheets
